UNITED STATES PATENT OFFICE

RICHARD R. MEAD, OF QUEENS VILLAGE, NEW YORK, ASSIGNOR TO MERGENTHALER LINOTYPE COMPANY, A CORPORATION OF NEW YORK

SLUG CASTING MACHINE

Application filed August 8, 1930. Serial No. 473,964.

This invention relates to slug casting machines, such as linotype machines of the general organization represented in U. S. Letters Patent to O. Mergenthaler No. 436,532, 5 wherein a type bar or slug is cast in a slotted mold up against a composed line of matrices which produce the type characters thereon. In these machines the matrices are usually provided with two type producing characters 10 or cavities, one a roman and the other an italic, these two characters being arranged in superposed relation on the matrix body and separated from each other by an intervening wall or partition, and it is the practice 15 to compose the matrices in line at an upper or lower level, or both, as may be required, in order to present the type producing characters of one kind or the other in registration with the mold slot. In casting slugs from 20 such two-letter matrices, it is apparent that the width of the mold slot is limited by the height of the matrix characters plus the thickness of the dividing wall or partition between the two superposed characters, as 25 otherwise the mold slot would open into the unselected matrix cavities and allow the metal to overflow from the mold, producing a defective slug and a "squirt" at the front. While ordinarily the thickness of a cast slug 30 corresponds to the height of the type characters thereon, it is common practice to cast the slug of an added thickness for spacing or leading purposes, say for example to cast a line of 12 pt. type characters on a 14 pt. body slug. In the case of a line of 14 pt. 35 characters however there is no margin left for leading purposes and hence it is only possible to cast a 14 pt. type line on a 14 pt. body or substantially so. 40 In view of the foregoing limitations as to the width of the mold slot, when it is necessary to produce a wide spacing of the type lines, separate leads or blank slugs of the required thickness must be inserted in the printing form between the successive slugs, this 45 practice requiring considerable time and labor and entailing extra expense in the casting, storage and handling of the leads. This is particularly true in large printing offices, such 50 as the United States Government Printing

Office, where the number of leads thus required to be cast and carried in stock runs into hundreds of thousands. In this connection it may be stated that the spacing of lines in certain classes of printed matter, such as 55 Congressional bills, is required to be as much as 12 pt., and this in the case of 14 pt. type characters, so that, as will be apparent, it is altogether out of the question to cast such slugs from two-letter matrices with the necessary added thickness, or in other words to 60 cast a 14 pt. type line on a 26 pt. slug body. In deed, since the thickness of the dividing wall between the matrix characters is somewhat less than 2 pt., it is never possible to cast slugs 65 of a body dimension greater than the height of the matrix characters plus the thickness of the dividing wall.

In attempting to overcome the foregoing defects it has been proposed to cast the leads 70 or blank slugs automatically after the casting of each printing slug and to assemble them in the galley in proper order. This scheme however has not proved entirely satisfactory because the casting of the leads between successive slugs slows up the operation of the machine and curtails production to such an extent as to make it impracticable.

Another attempt has contemplated the utilization of the rear jaw of the first elevator 80 as part of the casting mold, it being proposed to cut away the upper wall of the mold and cause the elevator jaw to enter the mold and shut off communication between the superposed matrix characters (see the Murray 85 Patent No. 1,567,857 of December 29, 1925). Besides possessing certain mechanical defects, this scheme is also objectionable in that it requires a special form of first elevator which is incapable of cooperating with the regular 90 form of mold and thus limits the machine to the casting of the special leaded slugs or else necessitates a reorganization of the parts to adapt the machine to cast slugs of ordinary or standard forms. Besides, this particular 95 scheme requires that the first elevator be presented to the mold always in its lowermost position so that the rear wall of the elevator will close the mold, whereas it is often the practice to arrest the elevator in a raised po- 100

sition in order to present the lower characters of the matrices in registration with the mold slot; hence, if this practice were resorted to, the mold would not be closed during casting 5 and would inevitably produce a bad "squirt".

The present invention aims to solve the problem involved without giving rise to the objections above-mentioned or any others of a troublesome nature. To this end, it is 10 proposed specifically to modify the regular form of mold in such manner that the upper side wall or cap portion will present a relatively fixed rear section which determines the effective width of the mold cavity and a re- 15 tractable complementary front section which restricts the width of the mold cavity at the front, so that the slug cast in the mold cavity will be narrow along its type character edge (that is to say no wider than the height the 20 type characters demand) but of much greater width below the type character edge (that is to say of such greater width as may be required for spacing purposes).

As is well known, in the regular form of 25 head-letter mold, the cap portion is formed on its inner or casting face with a series of transverse grooves and intermediate cores to produce a "recessed" or skeleton slug, and in carrying out this invention, it is preferred to 30 make use of a mold of this kind, altho ob- 35 viously a plain mold, such as is used for casting solid slugs, could be employed, if desired. In the case of such a head-letter mold, the front retractable section need only act to close the fore-and-aft grooves at the front, since it is these grooves which extend beyond the separating wall between the superposed matrix characters and allow communication of the mold with the upper or unselected characters.

40 If desired, the front mold section may be solid thruout, but in the present embodiment, as preferred, it is formed with inclined cuts or 45 grooves to register with the grooves in the rear section, so that the ribs cast on the slug will extend closer up to the printing edge and give a neater and more finished appearance to the cast slug. The forward edge of the front section however is made integral thruout so as to fit tightly against the proposed matrix 50 line, and the inner or casting face is flush with the inner or casting faces of the cores on the rear section, whereby the spacing rib grooves will be closed at the front and the recesses cast in the side of the slug will be straight and con- 55 tinuous as ordinarily.

In the use of the improved mold, it is mounted as usual upon a rotary disk which is operated periodically to present the mold, first in position for the casting of the slug, and later 60 in position for the ejection of the cast slug. In order to relieve the operator of all care and attention, means are provided for automatically retracting the front mold section as the mold is carried by the rotation of the disk 65 from casting to ejecting position and for

automatically restoring it (the front mold section) to operative position as the mold is carried from ejecting to casting position. In the present instance, such automatic operation of the mold section is effected by means 70 of a stationary cam track located on the hub about which the mold disk rotates, the mold section being connected to a frame having a roller running on the cam track.

It will now be seen that the improved mold 75 is capable of producing slugs with spacing ribs of any desired width without any limitation on account of the size of the matrix characters. For example, the mold shown in the accompanying drawings is adapted to cast a 80 14 pt. type line on a 26 pt. body, which is about the most extreme condition encountered in practice, and this with the same facility as slugs are cast in the regular molds.

As will be understood, the spacing ribs cast 85 on the slug function in the same way as separate leads inserted between adjoining slugs, so that the mere casting of the slugs automatically takes care of the required spacing or leading when the slugs are assembled in the printing form. Separate leads are therefore entirely dispensed with, as well as the time and labor involved in inserting and removing them in and from the printing form. Furthermore, no change is required to be made in 90 any part of the machine except in the mold itself, which, if need be, can be readily removed and replaced by a mold of standard form. However, since it is the common practice to provide a rotary disk with two or more molds, the machine may be equally adapted 95 for regular work simply by adjusting the mold disk to bring a standard mold into active position.

100 As a further feature of the invention it is also proposed to employ an improved set of trimming knives to dress the slugs as they are ejected from the improved mold. Ordinarily, the trimming knives are arranged with 105 their cutting edges in the same plane so as to act simultaneously on opposite sides of the slug as it is pushed thru them. In the present instance, however, one of the knives (the so-called left-hand knife) is set backward of the other or right-hand knife for a distance 110 about equal to that of the spacing ribs below the type character edge of the slug. In this way, no trimming of the slug takes place until the spacing ribs are brought into engagement with the right-hand knife, which is about the time the solid or unrecessed side of the slug is presented to the left-hand knife, and thereafter the two knives act together in 115 dressing the slug down to its proper thickness. This new arrangement of trimming knives 120 will avoid any tilting or rocking of the slug as it is pushed thru the trimming knives.

125 In the accompanying drawings:
130 Fig. 1 is a front elevation of a mold disk

of the regular linotype machine equipped with the present improvements;

Fig. 2 is a vertical cross section taken on the line 2—2 of Fig. 1, and showing the first 5 elevator in casting relation to the improved mold;

Fig. 3 is an enlarged face view of the improved mold, showing the front mold section in its retracted position;

10 Fig. 4 is a top plan view of the improved mold;

Fig. 5 is a vertical section taken on the line 5—5 of Fig. 3;

15 Fig. 6 is a cross sectional view of the parts, showing a slug in process of ejection and trimming; and

Fig. 7 is a perspective view of a slug cast in the improved mold.

The improved mold comprises, as usual, a 20 body portion A and a cap portion B, constituting the opposite side walls of the mold cavity, as well as intermediate liners C and D, constituting the opposite end walls of the mold cavity. As is well known, the liners C 25 and D are freely interchangeable with other liners of different lengths or thicknesses to vary the dimensions of the mold cavity. In the present instance, however, the mold shown is intended for casting a 26 pt. slug or a slug with a 26 pt. body, and in this connection it may be stated that the type characters to be cast on the slug have been selected as 14 pt., which is about the largest size now employed for two-letter matrices. The body 30 portion A and the liners C and D are of customary construction and require no special comment, but the cap portion B has been modified to give effect to the present invention in the manner now to be described.

40 As best shown in Figs. 2 and 5, the cap portion B is made up of a rear section 1 and a complementary front section 2, the combined width of these two sections equalling the width of the body portion A.

45 The rear section 1 is fixed in relation to the body portion A, being held in place upon the liners C and D by the usual fastening devices 3 at the opposite ends of the mold, and like the regular form of mold cap, it is formed 50 with a series of fore-and-aft thru-grooves 4 and intermediate cores 5 (Fig. 3). The depth of the grooves 4 (approximately 12 pt.) plus the width of the slot or space between the inner casting faces of the cores 5 and the upper or casting face of the body portion A 55 (approximately 14 pt.) determine the effective width of the mold cavity as a whole (26 pt.). This form of mold cap is employed 60 for casting recessed or skeleton slugs, the cores 5 producing recesses in one side of the slug and the grooves 4 producing spacing ribs on that side of the slug. For casting solid slugs, the cores 5 would be omitted, in which 65 case the casting face of the cap would be lo-

cated in a plane coinciding with the bottoms of the grooves.

The front mold section 2 is slidable outwardly and inwardly on the rear section 1, being provided at its rear side with three ribs 70 or tongues 7 (Fig. 4) fitted in grooves or guideways 8 formed on the forward side of the rear section, the two end ribs, as shown, being rabbetted to prevent the forward displacement of the front section. At its opposite ends, the section 2 is formed with rectangular openings to receive correspondingly shaped lugs 9 located on the upper ends of a pair of bars 10 passing inwardly thru openings cut in the liners C and D and the body portion A (Figs. 3 and 5). At their inner ends, the bars 10 are connected by a rigid cross bar 11, the several bars thus constituting a frame by means of which the mold section 2 may be slid upon the mold section 1 85 toward and from the body portion A.

The forward or matrix contacting edge of the mold section 2 is solid or integral thru-out and the same is true of its inner or casting face 12, which, as shown in Fig. 2, is flush with the inner casting faces of the cores 5 during casting. At its rear, however, the section 2 is formed with a series of inclined cuts or grooves 13 registering with the grooves 4 in the rear section 1 and constituting continuations thereof. These cuts or grooves 13 are not essential and may be omitted entirely, but they serve to finish off the ribs cast on the side of the slug and to bring them closer to the printing face. Notwithstanding the presence of the grooves 13, the front mold section 2, as will be observed from Fig. 2, closes at the front the grooves 4 of the rear mold section 1 and thus serves to restrict the width of the mold cavity at the front, as intended. The action of the front mold section would be exactly the same, were the cores 5 omitted, since it extends thruout the length of the mold cavity and consequently would partially close the mold cavity at the front even though the latter were continuous and adapted for casting solid or un-recessed slugs.

The improved mold is mounted in the usual way, as by means of screws 14 passing thru the body portion A upon a rotary disk E journaled upon a fixed or stationary hub E' (see Fig. 2). As is well known, the disk E at each cycle of operation of the machine is rotated periodically by the driving pinion E' (Fig. 1) so as to locate the selected mold first in a horizontal position (as in Fig. 1) for the casting of a slug, and later in a vertical position (as indicated by the dotted lines in Fig. 1) for the ejection of the cast slug. When the machine is at rest, the slotted mold stands in the ejecting position, being moved from that position to the casting position by a one-quarter rotation of the disk and later 130

returned to its original or ejecting position by a three-quarter rotation of the disk. It is during these periodical rotations of the mold disk that the front mold section 2 is moved to and from its operative position. Referring to Figs. 1 and 2, it will be noted that there is fixed to the hub E', as by means of cap screws 14^a, a continuous grooved cam 15 wherein engages a roller 16 journaled in a bracket 17, depending from the cross bar 11 of the frame before referred to. The shape of the grooved cam 15 is such that, when the mold is in casting position, as shown by the full lines in Fig. 1, the front mold section 2 is drawn down to and held firmly in its operative or casting position so as to restrict the mold cavity at the front (see Fig. 2), whereas, when the mold is in ejecting position, as shown by the dotted lines in Fig. 1, the mold section will be pushed, outwardly to its retracted position to permit the ejection of the cast slug (see Fig. 6). The actual movement of the mold section need take place only just before the mold reaches the ejecting and casting positions, but in order to render the operation smooth and quiet, the change of curvature of the cam is made gradual. As a matter of fact, and as can be seen from Fig. 1, the cam 15 is concentric for about three-quarters of its extent and presents an eccentricity throughout the remaining one-quarter of its extent. The highest point of the cam, indicated at 15^a, stands directly opposite the ejecting position or, more specifically, in the horizontal diameter of the mold disk so that the mold section 2 will be fully retracted at the time the mold stops in ejecting position. Since the mold disk always turns counter-clockwise, the one-quarter first rotation of the disk in carrying the mold from ejecting to casting position will result in the gradual drawing down of the mold section, the cam exerting its greatest pressure when the mold is in casting position, at which time the mold section must occupy its operative or mold restricting position. Later, when the disk makes its three-quarter rotation to carry the mold from casting to ejecting position, the cam, being concentric throughout the greater part of this motion, acts to maintain the mold section in its operative or unretracted position, this being desirable because of the back trimming of the slug which takes place during this rotation. Finally, when the mold approaches its ejecting position, the cam acts gradually to lift the mold section and to retract it fully by the time the mold arrives in the ejecting position.

Fig. 2 shows a composed line of matrices X in casting relation to the improved mold. As will be noted, the matrices are each formed with two superposed type producing characters or cavities x¹ and x² separated from each other by an intervening wall or partition x³. In the illustration given, some of

the matrices of the composed line are supported in the first elevator F (which is of regular form) at a lower level to present their upper or roman characters in operative position, while others are supported in the elevator at an upper level to present their lower or italic characters in operative position. The construction of the casting parts and their mode of operation are so well known that a detailed description would be superfluous. Suffice it to say that after the composed line has been transferred into the first elevator, the latter moves downwardly into the position shown in Fig. 2 to locate the line of selected matrix characters in registration with the mold cavity. Prior to casting, the mold disk is advanced to bring the mold into contact with the composed line which closes the mold cavity at the front, and then the mouthpiece G of a melting pot is advanced into contact with the rear face of the mold to close the mold cavity at the rear, the molten metal then being discharged by a pump into the mold and up against the composed line of matrices for the production of the type bar or slug.

By looking at Fig. 2 it will be apparent at once that, if the grooves 4 in the rear section 1 of the mold were extended clear thru to the front of the mold, as in the regular form of mold, the grooves would overlap or open into the upper characters of those matrices whose lower characters are in casting position, and as a result the molten metal would flow out of the mold past the matrices, causing not only an imperfect slug, but producing a squirt. In the improved mold, on the other hand, the front section 2 closes the grooves 4 at the front and thus shuts off communication between them and the upper matrix characters, and more, actually restricts the mold cavity to the area defined by the selected matrix characters in casting position. Since these characters are of 14 pt. size, the front mold section 2 serves to restrict the mold cavity at the front to a corresponding width or, in other words, to the width of the slot or space defined by the casting face of the body portion A and the inner faces of the cores 5.

Fig. 7 shows a slug Y, such as is produced by the improved mold. As will be noted, the slug comprises a body portion Y¹ (of 14 pt. size) cast in the mold slot proper last referred to, a line of type characters Y² (of 14 pt. size) cast in the matrix cavities, and a series of transverse spacing ribs Y³ cast in the grooves 4, the intermediate blank spaces or recesses being produced by the cores 5. The upper beveled ends Y⁴ of the ribs Y³ are cast in the grooves 13 of the front wall section 2. Had these grooves 13 been omitted, the ribs Y³ would present straight or squared off shoulders, hence the presence of the grooves.

In Fig. 6 the mold is shown in ejecting position and the slug Y in process of ejection by an ejector blade H, which is thrust thru the mold in the customary way to push the 5 slug forward between the pair of trimming knives at the front. In the present embodiment, the trimming knives are arranged one in advance of the other for the reason previously stated. Thus, the right-hand adjustable knife J is arranged in the usual way to dress the spacing ribs Y³, while the left-hand non-adjustable trimming knife J¹ is set backwardly of the right-hand knife at a distance about equal to the distance the spacing ribs 10 3 are located below the type character edge of the slug. Hence, when the slug enters between the two knives, no trimming will take place until the spacing ribs reach the right-hand knife. At this time the opposite 15 or solid side of the slug will have reached the left-hand knife J¹ and the two trimming knives will then act together in dressing down the slug. In this way any tilting or 20 rocking of the slug, while in process of trimming, is avoided. The part J², which stands forward of the left-hand knife J¹, is not intended for trimming, being set back of the line of the trimming edge; it merely acts as a guide to direct the slug until it comes under 25 the influence of the two trimming knives.

In the accompanying drawings the invention has been shown merely in preferred form and by way of example, but obviously many 30 changes and variations may be made therein and in the mode of application without departing from its spirit. It should be understood, therefore, that the invention is not limited to any specific form or modification except in so far as such limitations are set 35 forth in the appended claims.

Having thus described my invention, what I claim is:

1. A slug casting mold comprising side and 40 end walls which define between them a cavity 45 wherein the slug is cast, one of the side walls of the mold being fixed as a whole, and the other side wall thereof presenting a relatively fixed rear section which determines the effective width of the mold cavity, and a retractable complementary front section which restricts the width of the mold cavity at the front.

2. A slug casting mold comprising side and 50 end walls which define between them a cavity wherein the slug is cast, one of the side walls of the mold presenting a rear section formed with fore-and-aft grooves and intermediate cores, and a complementary front section closing said grooves at the front.

3. A slug casting mold comprising side and 55 end walls which define between them a cavity wherein the slug is cast, one of the side walls of the mold presenting a rear section formed

with fore-and-aft grooves and intermediate cores, and a complementary front section enclosing said grooves at the front, said front section being retractable after casting to permit the ejection of the cast slug. 70

4. A slug casting mold according to claim 2, characterized by the fact that the front section therein referred to has an integral front edge whose inner or casting face is flush with the inner casting faces of the cores of the rear section. 75

5. A slug casting mold according to claim 2, characterized by the fact that the front section therein referred to has an integral front edge whose inner or casting face is flush with the inner casting faces of the cores of the rear section, and characterized by the further fact that said front section is formed in its rear face with inclined cuts or grooves registering with the grooves in the rear section. 80

6. A slug casting mold comprising side and end walls which define between them a cavity wherein the slug is cast, one of the side walls of the mold presenting a relatively fixed rear section formed with fore-and-aft grooves and intermediate cores, and a retractable complementary front section formed in its rear face with inclined cuts or grooves registering with those in the rear section and with an integral front edge whose inner or casting face is flush with the inner casting faces of the cores in the unrefracted position of the front section. 85

7. A slug casting mold comprising a body portion, an overlying cap portion, and intermediate liners, said parts defining between them a mold cavity wherein the slug is cast, the body portion of the mold being fixed as a whole, and the cap portion of the mold presenting a relatively fixed rear section which determines the effective width of the mold cavity and a retractable complementary front section which restricts the width of the mold cavity at the front. 90

8. A slug casting mold comprising a body portion, an overlying cap portion, and intermediate liners, said parts defining between them a mold cavity wherein the slug is cast, the cap portion of the mold presenting a relatively fixed rear section formed with fore-and-aft grooves and intermediate cores, and a retractable complementary front section closing said grooves at the front. 105

9. In a slug casting machine, the combination of a mold comprising side and end walls which define between them a cavity wherein the slug is cast, one of the side walls of the mold being fixed as a whole and the other side wall thereof presenting a relatively fixed rear section which determines the effective width of the mold cavity and a retractable complementary front section which restricts the width of the mold cavity at the front, and automatic means for effecting the retraction 110

120

125

130

of the front mold section after casting to permit the ejection of the cast slug.

10. In a slug casting machine, the combination of a mold comprising side and end walls which define between them a cavity wherein the slug is cast, one of the side walls of the mold being fixed as a whole, and the other side wall thereof presenting a relatively fixed rear section which determines the effective width of the mold cavity and a retractable complementary front section which restricts the width of the mold cavity at the front, means for moving the mold from casting to ejecting position and vice versa, and 15 automatic means for retracting the front mold section when the mold is moved from casting to ejecting position and for restoring it to operative position when the mold is moved from ejecting to casting position.

20 11. In a slug casting machine, the combination of a mold comprising side and end walls which define between them a cavity wherein the slug is cast, one of the side walls of the mold being fixed as a whole, and the 25 other side wall thereof presenting a relatively fixed rear section which determines the effective width of the mold cavity and a retractable complementary front section which restricts the width of the mold cavity at the 30 front, a rotary disk wherein the mold is mounted and operable periodically to carry the mold from casting to ejecting position and vice versa, and means actuated by the 35 rotation of the disk to retract the front mold section as the mold is carried from casting to ejecting position and to restore it to operative position as the mold is carried from ejecting to casting position.

12. In a slug casting machine, the combination of a mold comprising side and end walls defining between them a cavity wherein the slug is cast, one of the side walls of the mold presenting a relatively fixed rear section formed with fore-and-aft grooves 40 and intermediate cores, a retractable complementary front section which closes said grooves at the front, and automatic means for effecting the retraction of the front mold section after casting to permit the ejection 45 of the cast slug.

13. In a slug casting machine, the combination of a mold comprising side and end walls defining between them a cavity wherein the slug is cast, one of the side walls of the mold presenting a relatively fixed rear section formed with fore-and-aft grooves and intermediate cores, a retractable complementary front section which closes said 50 grooves at the front, means for moving the mold from casting to ejecting position and vice versa, and automatic means for retracting the front mold section when the mold is moved from casting to ejecting position and 55 for restoring it to operative position when 60

the mold is moved from ejecting to casting position.

14. In a slug casting machine, the combination of a mold comprising side and end walls which define between them a cavity wherein the slug is cast, one of the side walls of the mold presenting a relatively fixed rear section which determines the effective width of the mold cavity, a retractable complementary front section which restricts the width of the mold cavity at the front, a rotary disk wherein the mold is mounted and operable periodically to carry the mold from casting to ejecting position and vice versa, a stationary hub on which the mold disk is rotatably mounted, and a cam located on the stationary hub and operative upon the front mold section to effect its retraction as the mold is carried from casting to ejecting position and to restore it to operative position as the mold is carried from ejecting to casting position.

15. The combination as specified in claim 9, characterized by the fact that the mold therein referred to comprises a body portion, an overlying cap portion, and intermediate liners, said parts defining between them the mold cavity wherein the slug is cast, and characterized by the further fact that the side wall of the mold presenting the relatively fixed rear section and the retractable complementary front section is constituted by the cap portion of the mold.

16. In a slug casting machine, the combination of a composed line of two-letter matrices presenting a line of matrix characters or cavities, some or all of said characters being the lower characters of the matrices in the composed line, and a slotted mold to cooperate with the line of matrix characters, the effective width of the slot being great enough to overlap the upper characters of the matrices whose lower characters are in casting position, said mold comprising a cap portion presenting a relatively fixed rear section and a retractable complementary front section which shuts off communication between the mold slot and said upper matrix characters, and automatic means for retracting the front mold section after casting to permit the ejection of the cast slug.

17. In a slug casting machine, the combination of a composed line of two-letter matrices presenting a line of matrix characters or cavities, some or all of said characters being the lower characters of the matrices in the composed line, and a slotted mold to cooperate with the line of matrix characters, the upper wall or cap portion of the mold comprising a relatively fixed rear section formed with fore-and-aft grooves overlapping the upper characters of the matrices whose lower characters are in casting position, and a retractable complementary front section shutting off communica-

cation between said grooves and said upper matrix characters, and automatic means for retracting the front mold section after casting to permit the ejection of the cast slug.

5 18. In a slug casting machine, the combination of a mold for casting a slug solid on one side and formed with ribs on the opposite side, said ribs being located a given distance below the type character edge of the
10 slug, and a pair of trimming knives between which the slug is forced after casting, the two knives being arranged with their cutting edges disposed one in advance of the other for a distance approximately equal to
15 the distance the slug ribs are located from the type character edge, whereby rocking and tilting of the slug during trimming is avoided.

In testimony whereof, this specification
20 has been duly signed by:

RICHARD R. MEAD.
